UNITED STATES PATENT OFFICE.

CHARLES BOLDT, OF CINCINNATI, OHIO.

DESIGN FOR A BOTTLE.

No. 39,921.

Specification for Design.

Patented April 20, 1909.

Application filed March 6, 1909. Serial No. 481,856. Term of patent 14 years.

To all whom it may concern:

Be it known that I, CHARLES BOLDT, a citizen of the United States, residing at Cincinnati, in the county of Hamilton and State of Ohio, have invented a new, original, and ornamental Design for Bottles, of which the following is a specification, reference being had to the accompanying drawing, forming part thereof.

Figure 1 is a side elevation of a bottle,

showing my new design and Fig. 2 is a perspective view thereof.

I claim—

The ornamental design for a bottle as shown.

CHAS. BOLDT.
